UNITED STATES PATENT OFFICE.

CHARLES C. GRUHLER, OF BELLEVUE, KENTUCKY.

STATIONERY.

1,229,442.

Specification of Letters Patent. Patented June 12, 1917.

Application filed October 6, 1915. Serial No. 54,451.

To all whom it may concern:

Be it known that I, CHARLES C. GRUHLER, residing at Bellevue, Campbell county, State of Kentucky, have invented certain new and useful Improvements in Stationery, of which the following is a clear, full, and exact description, attention being called to the drawing which accompanies this application and forms a part thereof.

10 This invention relates to stationery, and concerns more particularly letter paper and envelopes where they are contained in one sheet. The invention consists of the particular arrangement and combination whereby 15 the letter sheet becomes available for use to form the envelop for the letter, part of the letter sheet providing the face of said envelop and bearing name and address of the recipient, as well as the name and address of the sender.

The following specification contains a description of the invention which is also pointed out in the claim at the end thereof and illustrated in the accompanying drawing in which:

Figure 1, shows the letter sheet flat and ready to receive the writing, inscribed matter being also shown.

Fig. 2, in perspective view shows it in the act of being folded up to form the envelop.

Fig. 3, in a cross section of the preceding figure shows the act of folding nearing completion.

Figs. 4 and 5, show front and rear-sides 35 respectively of the envelop into which the sheet has been transformed.

Fig. 6, shows the reverse side of the sheet after the letter has been opened.

Fig. 7, in a view similar to Fig. 3, shows 40 the letter sheet used for a one-cent postage (unsealed) letter.

Fig. 8, shows a longitudinal edge-view (the right edge) of Fig. 7.

Fig. 1, shows the face side of the letter sheet, with the letter-head of the writer and a letter written on the sheet below the letter-head.

The letter-portion of the sheet is thereaf- 50 ter doubled up and folded in a manner as indicated by a dotted line shown at 8, and part 9 below this line, in extent substan- tially one third of the sheet and one half of the letter portion thereof, is turned up and laid over against part 10 above this 55 line so that the front sides of these parts,

with the writing on them lie against each other.

The sheet is folded again, this time in opposite direction and in a manner as indicated by a dotted line shown at 11 and below 60 the name and residence of the addressee, the doubled-up portion which comprises super- posed parts 9 and 10, being folded against part 12 so that the rear side of part 10 lies against the rear side of part 12. Figs. 2 and 65 3 illustrate the manner of folding. The front-side of this part 12, of the letter-portion of the sheet forms also the face-side of the envelope and contains the letter head of the writer which serves also as his return 70 address in case the same is required. It also bears the written heading of the letter which serves as the address for the envelope.

The closure is completed by pasting flaps 75 13, 14 and 15, which project from three edges of part 12, against the rear side of part 9 of the sheet, said flaps being gummed on the rear side of the sheet. If any inclo- sure is to go with the letter, this is placed 80 in the space 16, Fig. 3, between the rear sides of parts 10 and 12 and before all the flaps are pasted down, said space forming thereby a completely closed pocket.

It is realized that access to the written 85 part of the message is not entirely excluded but in most of the usual business corre- spondence this is not deemed objectionable, especially in view of the fact that during the rapid handling of the letters in transit the chances for reading are quite limited. 90

The sheet may also be used as a circular which goes at the reduced or one-cent rate. In this case it is manipulated substantially in the same manner except that circular matter occupies parts 10 and 9 on the face 95 of the sheet in place of written matter.

Flaps 14 and 15 are pasted down as shown in Fig. 8 to maintain the sheet in its folded condition. An open pocket results between the rear sides of parts 10 and 12 as shown 100 at 17 in Fig. 7 which may be utilized as an envelop to send samples for instance or additional circular matter, or it may be used as an envelop to send circular matter in place of the matter placed on parts 10 and 105 9 of the sheet. Flap 13 forms the flap for this envelop and after the matter to be mailed is placed into pocket 17, this flap is turned into the pocket so as to retain the in- closure. Observe dotted lines in Fig. 7. 110

The letter is opened by cutting it along the three edges shown at 18 in Fig. 5 and where the flaps join the main sheet so that said flaps remain on the rear side of part 9 5 as shown in Fig. 6 thereby avoiding mutilation of the face of the sheet.

Having described my invention I claim as new:

An envelop formed out of a letter sheet 10 which has been folded in opposite directions along two lines so as to produce three substantially equal-sized superposed parts and of which sheet the middle and the lower part before folding constitute the writing 15 face and after folding lie with their face sides against each other, the part above them, being the top part of the sheet before folding, bearing a printed letterhead also on the writing face side of the sheet and 20 which part after folding of the sheet forms

also the face of the envelop, this top part having on each of its three free edges a pasting flap gummed on the rear side of the sheet and whereby this top part after the sheet is folded is secured against the rear- 25 side of the lower part with the middle part of the sheet between them, thereby closing the envelop in a manner that when the flaps are cut for opening the envelop the severed flaps are all on the rear side of the sheet so 30 as to avoid defacing of the writing face which bears the message and leaving the same entirely clear.

In testimony whereof I hereunto affix my signature in the presence of two witnesses. 35

CHARLES C. GRUHLER.

Witnesses:

C. SPENGEL,
A. JOHNSON.
